UNITED STATES PATENT OFFICE.

WILLIAM MILLARD, OF NEW YORK, N. Y., ASSIGNOR TO CARBON DESTROYER CORPORATION, OF NEW YORK, N. Y., A CORPORATION OF NEW YORK.

APPARATUS FOR MOISTENING CARBURETED MIXTURES FOR GAS-ENGINES.

1,329,252.

Specification of Letters Patent.

Patented Jan. 27, 1920.

Application filed November 21, 1917. Serial No. 203,290.

To all whom it may concern:

Be it known that I, WILLIAM MILLARD, a subject of the King of Great Britain, residing at the borough of Manhattan, city, county, and State of New York, have invented certain new and useful Improvements in Apparatus for Moistening Carbureted Mixtures for Gas-Engines, of which the following is a specification, reference being had to the accompanying drawings.

This invention relates to improvements in apparatus for impregnating a combustible gas with water vapor, and particularly to improvements in apparatus by means of which air is made moist and is then incorporated, in a moist condition, in a carbureted mixture that is burned in the working cylinder of a gas-engine, or like motor, of an automobile; and an object of this invention is to provide an apparatus of the character just described which will prove simple in construction, comparatively cheap in manufacture and efficient in operation and use. Another object of this invention is to provide an apparatus of the kind hereinbefore referred to by means of which the results obtained will be uniform in character. Other features of this invention will be referred to hereinafter.

30. In the drawings illustrating the principle of this invention and the best mode now known to me of applying that principle, Figure 1 is a central vertical section through the tank or reservoir of the air-moistener; Fig. 2 illustrates the latter connected to the intake manifold of a gas-engine or like motor; Fig. 3 illustrates a modification of the construction shown in Fig. 2, the air-moistener being connected to the carburetor; Fig. 4 shows, in central vertical section, a modified form of the air-moistener illustrated in Fig. 1, the admission of the air being controlled by a valve arranged over an air-opening in the base of the reservoir or receptacle that holds the water or solution; Figs. 5 and 6 are fragmentary sections in which a flap valve and a ball valve, respectively, are shown; and Figs. 7 and 8 are plan views showing the disklike check valve of Fig. 4 and the flap valve of Fig. 5, respectively.

a denotes a cup-shaped, transparent vessel which serves as a receptacle for holding water or a suitable solution *b*, and the exterior of the mouth of which is formed with

screw-threads *c*, by the provision of which one is enabled to screw, upon the receptacle *a*, its cover *d*. In the latter, there is formed an opening *f* which is normally kept closed by means of a stopper *g*, which is screwed thereinto and which, when it is desired to replenish the supply of water *b* in the vessel *a*, is removed; and, since the latter is transparent, the state of the water-supply in the receptacle *a* may be observed at any time. A gasket or washer *e* is interposed between the mouth of the vessel *a* and the inner face of the cover *d* and serves to make the joint between the vessel and its cover air-tight. Near the center of the cover *d*, there is formed a boss *h* having, in its top, a socket or cavity *h'*. The bottom *h''* of the socket *h'* serves as a support for the valve *i*, which is screwed into the bottom *h''* and which is formed with a disklike head *i'*, having a milled periphery *i''*. Projecting downwardly from the boss *h*, there extends an air-tube *j*, the central passage *j'* in which communicates at its upper end with ports *k* formed in the bottom *h''* of the socket *h'*. By turning the milled head *i'* of the valve *i*, the position of the same may be so adjusted as to close entirely the ports *k*, leave them fully open or close them only partially, whereby the amount of air admitted to the air-passage *j'* may be regulated. A vertically-extending leaf-spring *m* is arranged adjacent to the boss *h* and is provided, at its upper end, with a detent or catch *m'* that is designed to engage automatically in the milled, peripheral surface *i''* of the valve-head *i'* and serves thus to retain the valve in its adjusted position. The lower end of the air-tube *j* is formed with openings or ports *j''* through which the air escapes from the air-tube *j* and passes into the water *b*, through which the air flows upwardly into the air-space *b'*. One end of a conduit *n* communicates with the latter space, while the other end of the conduit *n* communicates freely with the intake manifold *o* of a gas-engine or like motor *o'*.

When the piston (not shown herein) of the motor *o'* moves downward on its sucking stroke, an explosive or combustible mixture is drawn through the manifold *o* from the carburetor *p* and enters the working cylinder of the gas-engine. At the same time, air is drawn from outside the receptacle *a*, through the air-ports *k*, into the pas-

2
sage j' of the air-tube j and flows thence, through the ports j'' and the water (or solution) b , into the air-space b' thereabove, whence the air, now moistened with water-vapor, flows through the conduit n into the intake manifold o , wherein it mixes with the working fluid drawn therethrough from the carbureter p , as has been hereinbefore described.

10 As is shown in Fig. 3, the discharge end of the conduit n may be arranged to empty into the carbureter p , instead of directly into the intake manifold o . Indeed, the point of attachment of the outlet end of the conduit n is immaterial, so long as the moistened air from the water-containing reservoir a is permitted to mingle with the working fluid from the carbureter p .

15 The air-tube j may be dispensed with and 20 the air admitted to the receptacle through the bottom thereof, as is shown in Figs. 4 to 6, both inclusive. In the modified construction illustrated in Fig. 4, the vessel a' is formed with an opening a'' , in its bottom, 25 for the admission of air thereinto; and the flow of air through the opening a'' is controlled by a check valve q , which, in the particular form illustrated, is a disk of rubber or other suitable material cemented at q'' 30 to the bottom of the vessel a' and having intersecting cuts q' near its center; and the cut portion overlies the air-opening a'' . In the modification illustrated in Fig. 5, the air-opening a'' is controlled by a flap valve 35 r secured to the bottom of the receptacle a' by means of the fastener r' . In Fig. 6, there is shown a modified form in which the

boss h' projects downwardly from the base of the vessel a' , while escape of water through the air-passage s is prevented by the ball-shaped check-valve s' , the casing s'' of which is formed with ports t for the flow of the incoming air into the water b .

40 Instead of water, a mixture of water with alcohol may be used to moisten the air; and a solution of hydrogen peroxid may be made to serve the same purpose. Other suitable 45 solutions will readily suggest themselves to all skilled in this art.

50 I claim:

A unitary air-moistening device comprising a reservoir adapted to contain liquid and air and having formed directly in and by one of its walls a passage intermediate the lower portion of its interior and the atmosphere, a valve applied directly to and carried by the said wall of the reservoir and which controls the flow of air through said passage into the lower portion of the reservoir, and a conduit carried by one wall of the reservoir, in communication with the upper portion of the interior thereof and capable of direct connection to a conduit for carbureted air.

55 Signed at the borough of Manhattan, city, county and State of New York, this fourteenth day of November, A. D. 1917, in the presence of the two undersigned witnesses.

60 WILLIAM MILLARD.

Witnesses:

65 GEORGE E. BROWN,
JAMES HAMILTON.
